J. F. LESSING

AUTOMATIC WEATHER STRIP

Filed August 31, 1925

Inventor,
John F. Lessing
By Arthur H. Durand, Atty.

UNITED STATES PATENT OFFICE.

JOHN F. LESSING, OF ST. JOSEPH, MICHIGAN.

AUTOMATIC WEATHER STRIP.

Application filed August 31, 1925. Serial No. 53,468.

To all whom it may concern:

Be it known that I, JOHN F. LESSING, a citizen of the United States, and resident of St. Joseph, Berrien County, Michigan, have invented a certain new and useful Improvement in Automatic Weather Strips, of which the following is a specification.

This invention relates to weatherstrips for the lower edges of outside doors, such as storm doors, or doors for the front and rear of houses, or other buildings, to keep the cold air from coming in under the lower edge of the door.

Generally stated, the object of the invention is to provide a novel and improved construction, whereby a weather-strip of this kind will be operative and effective to produce the desired result, when the door is closed, by tightly sealing the slight space ordinarily found between the lower edge of the door and the threshold, but which will ordinarily rise when the door is swung inwardly, thereby to pass readily over a carpet or rug, or anything else on the floor immediately inside of the door, and which will then automatically move downwardly when the door is closed, thereby to again make firm contact with the threshold of the door, to prevent cold air from coming in under the door.

It is also an object of the invention to provide certain details and features of construction and combinations tending to increase the general efficiency and desirability of an automatic door threshold weatherstrip of this particular character.

To the foregoing and other useful ends, the invention consists in the matters hereinafter set forth and claimed, and shown in the accompanying drawings, in which—

Figure 1 is an inside elevation of the lower portion of a door, and the adjacent portions of the door frame and threshold, equipped with an automatic weatherstrip for the lower edge of the door, embodying the principles of the invention;

Figure 2 is a horizontal section, on a larger scale, on line 2—2 in Figure 1; and

Figure 3 is a vertical section, on a still larger scale, on line 3—3 in Figure 1.

As thus illustrated, the invention comprises a hinge 1, secured to the door frame 2, immediately below the door hinge 3, in the manner shown, and provided with a long strap 4 having slots 5 through which screws 6 are inserted into the door 7. This

latter may be of any suitable character. The hinge 1 is so located that the strap 4 slides back and forth on the screws 6, endwise, when the door is opened and closed. 60 The weatherstrip 8 may be composed of any suitable material, such as metal, provided at its lower edge with soft material, such as rubber, to engage the threshold 9 of the doorway. The weatherstrip 8 is preferably 65 provided with a slot 10, through which a screw 11 is inserted into the door, so that the weatherstrip is movable up and down, and for this purpose guides 12 for the ends 70 of the weatherstrip are applied to the side edge portions of the door, whereby the weatherstrip is free to move up and down within limits.

The portions 13 of the weatherstrip are provided with pins or screws 14, which extend through oblique cam slots 15, in the strap 4, previously mentioned. These slots 15 are disposed at such an angle, it will be seen, that the relative endwise movement of the strap 4, when the door is opened, will 75 cause the pins or screws 14 to rise in the slots 15, thus lifting the weatherstrip 8 a distance above the floor, so that it will pass over a rug or carpet, or anything else laid on the floor immediately inside the door. 80 Then, when the door is closed, the endwise movement of the strap 4, and the consequent cam action of the edges of the slots 15 in co-operation with the pins or screws 14, 85 will cause the weatherstrip 8 to move down 90 into engagement with the threshold 9, previously mentioned.

Thus, an automatic weatherstrip is provided for the lower edge of the door, adapted to automatically engage the threshold 95 when the door is closed, to prevent cold air from entering under the door. This automatic weatherstrip, when the door is opened, automatically rises to provide full clearance 100 for the lower edge of the door that passes over a carpet or rug laid on the floor immediately inside of the door.

It will be understood, of course, that the invention is not limited to the exact construction shown and described, as an automatic weatherstrip for the lower edge of a door, or for a window, or other outside closure, of this general character, may have any suitable construction, so that it will automatically move up and down when the 110 door is opened and closed, without departing from the spirit of the invention.

While the invention is shown in the form of a so-called weatherstrip, it will be understood, of course, that this device for preventing the passage of a draft below the lower edge of the door may, of course, be applied to either an outside or an inside door, or wherever there is any danger of an undesirable draft under the lower edge of the door.

10 Without disclaiming anything, and without prejudice to any novelty disclosed, what I claim as my invention is:

15 1. The combination with a door or other outside closure, of an automatic weatherstrip for the lower edge thereof, comprising instrumentalities for causing the weatherstrip to automatically move up and down when the door is opened and closed, said instrumentalities comprising a hinge connection 20 between the door and the doorway, comprising a member having movement horizon-

tally and endwise relatively to the door, when the door is opened or closed, said member having a camming action with the weatherstrip, whereby said endwise movement causes the weatherstrip to rise when the door is opened, and causes the weatherstrip to move downward when the door is closed.

2. A structure as specified in claim 1, said hinge connection being out of line with the hinges of the door, so that said door swings about one axis, while said member swings about another axis.

3. The improved automatic weatherstrip 25 for a door or other closure, as specified in claim 1, having the slot 10 and screw 11 for the middle portion of the strip, and guides 12 for the ends of the strip.

Specification signed this 27th day of 40 August, 1925.

JOHN F. LESSING,
